TIME FUSE

Richard H. Whitehead, New Haven, Conn., assignor, by mesne assignments, to the United States of America

Application October 21, 1939, Serial No. 300,551

3 Claims. (Cl. 102—84)

1

This invention relates to time fuses in which the firing is controlled by a clock train actuated by a power dependent upon rotational forces for motivation, as for example centrifugal weights.

Such fuses customarily have an escapement device of the self-starting type, that is in which the escapement device itself may be started in motion from rest by the actuating power and they also have a mechanism for preventing the escapement from starting until the act of firing. In such fuses inaccuracy has been found in the timing due in part to the fact that there are variations in the friction of the time train which it is impossible to eliminate with existing methods and probably also in part due to variations in the exact instant at which the rotational forces become effective.

In the manufacture of timing devices such as clocks and the like, the friction of the train may be directly tested by operating the movement under its own reduced power but such operation is not feasible in time fuses because the actuating power is due to rotational speeds of from twelve to twenty-four thousand revolutions per minute.

It is an object of this invention to overcome these objections by providing an auxiliary source of actuating power which will be sufficient just to operate the train in response to its own friction and which at the same time will be capable of adding sufficient force to the rotational forces positively to start the escapement device in operation as soon as it is released by the releasing mechanism.

The centrifugal weights customarily employed in fuses of this kind are attached to drive gear segments and hence operate on some portion of a sine curve. This itself causes variations in the timing with variations in power. If the weights are so located as to give effective starting power through centrifugal force the actuating force may so fall off at the latter portion of the time sequence as to make the operation unreliable. These defects cannot be overcome by increase of power because such increase may damage the elements so as itself to be a source of inaccuracy or failure.

It is a further object of this invention to so combine the rotational forces with a supplementary spring force that a more uniform distribution of power throughout the time range of the fuse may be assured.

The invention accordingly comprises the features of construction, combination of elements and arrangements of parts which will be ex-

2

emplified in the construction hereinafter set forth and the scope of the application of which will be indicated in the claims.

For a fuller understanding of the nature and objects of the invention, reference should be had to the following detailed description, taken in connection with the accompanying drawing, in which:

Fig. 1 is an elevation of a time fuse embodying this invention.

Fig. 2 is a section on the line II—II of Fig. 1 showing the actuating power.

Fig. 3 is a bottom plan of the timing mechanism.

Fig. 4 is a diagram showing the manner in which the power is maintained substantially uniform throughout the range of the fuse.

In the drawings the numeral 10 designates the cap of the fuse fitting over the base 11 and housing between them the timing mechanism 12. The cap 10 is here illustrated as made of a single piece but it forms no part of the present invention and it may be made in two parts in accordance with present conventional practice. The cap 10 is held on the base 11 by spring means 13 locked with screws 14.

The time mechanism 12 comprises a vibrator 15 carrying verge pins 16 adapted to release an escapement wheel 17 which in turn is driven by a gear train, not shown, from centrifugal weights 18 through a pinion 19 and being constructed and arranged to release a firing pin 20 after a period of time predetermined by the setting of the cap 10 upon the base.

As here illustrated the centrifugal drive weights 18 comprise discs having teeth 18a cut in a portion of the periphery thereof, the remainder being uncut and having openings 18b opposite the teeth to balance the disc and mounted upon each of these discs is a metallic mass 21 so placed as to determine the maximum value of the centrifugal drive force and to determine at what point in the time sequence this maximum will be exerted.

Mounted on the shaft 22 of each of these weights 18 is a coil spring 23 having one leg 24 engaging the frame at 25 of the timing mechanism and the other leg 26 engaging the segment as for example by bearing against the mass 21.

These springs 23 exert their maximum force at the beginning of the time sequence and decrease toward the end thereof, but are so chosen that they will exert sufficient power to overcome the normal friction of the mechanism and escapement. In order to prevent starting of the

mechanism until the shell leaves the bore of the gun there is provided a dog 15a constructed and arranged in the usual manner. The centrifugal weights, with their change in radius of action during their movement, create an effective drive torque which varies during the time sequence of the mechanism according to some portion of a sine curve. By choosing the location of the weights 18, with reference to the coil springs 23, the variation in drive force of the weights may be adjusted in part to compensate for the variations in drive force of the spring so as to produce a more nearly uniform torque during the time required. This decreases the total maximum driving torque compared to that minimum required to drive the train and hence increases the reliability of the timing and prevents undue wear upon the pivots and bearings.

In Fig. 4 there is shown the manner in which the actual power of the drive spring and the centrifugal weights may be combined to produce the actual driving torque. In this diagram the time is measured from the time the projectile leaves the muzzle of the gun when it has already attained its full rotational velocity. From then on, ignoring the loss of velocity during flight, the rotational effect during flight will be constant as illustrated in the diagram by the line A.

The turning force upon the members 18 of the springs will fall off rapidly toward the end, as shown by the line B, but the effect upon the members 18 of the constant centrifugal force A, at any instant will depend on the angular position of the masses 21 about the shaft 22. This effect is shown in the line C which as will be seen, has a dip down at both the beginning and the end. This is a serious defect, because, if the initial force is great enough to start the movement, and at the same time the final force is kept strong enough to continue the movement without loss of timing, then the force during the middle period would be excessive.

These defects are overcome by adding to the centrifugal force a spring tension designed to build up the rotational effect at the beginning of the stroke, thus permitting a design where the maximum of the centrifugal weight curve can be placed later in the cycle, and thus secure more force at the end of the timing period.

We have here illustrated the rotational effect as constant during flight, but in practice there is an actual slowing down of the rotational force which has heretofore been enough to ruin the timing of the fuse during the last seconds of a long flight. With this invention it is possible to so build up the end energy that the accuracy of timing can be maintained without encountering the other evils of which we have spoken.

In accordance with this invention the device may be tested during the construction by being so adjusted that the coil springs 23 will actually drive the escapement at slow speed even while the shell is at rest, that is while the centrifugal weights are making no contribution to the power drive. This driving by the springs may be feeble and may be inadequate for reliability but it serves as an accurate measure of the internal friction of the mechanism. The springs are preferably so chosen relative to the friction of the device that the springs will drive the mechanism throughout the entire time sequence and in this manner the friction at every point in the movement of the time train, may be determined.

By the employment of these springs it is possible to construct centrifugally driven time fuses

and practically to adjust them in their completely assembled form and thus to insure accuracy and reliability in operation.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described and all statements of the scope of the invention which, as a matter of language, might be said to fall therebetween.

Having described by invention, what I claim as new and desire to secure by Letters Patent, is:

1. A fuse for projectiles having a time train and an escapement and a firing pin releasable by the time train, a pair of centrifugal drive weights pivotally mounted symmetrically in respect to the longitudinal axis of the projectile, a pair of drive springs symmetrically mounted in respect to the longitudinal axis of the projectile one adjacent each of said centrifugal weights, each of said symmetrically mounted springs having one end in engagement with the frame of the mechanism and having its other end in driving engagement with the corresponding pivotally mounted centrifugal weight, said centrifugal drive weights comprising disc members each having a mass mounted thereon so placed as to determine the maximum value of the centrifugal drive force and to determine the point in the time sequence at which the maximum will be exerted, said centrifugal weight discs being pivoted substantially centrally thereof, said symmetrical drive springs comprising coil springs mounted at the central pivots of said centrifugal weight discs.

2. A fuse for projectiles having a time train and an escapement and a firing pin releasable by the time train, a pair of centrifugal drive weights pivotally mounted symmetrically in respect to the longitudinal axis of the projectile, a pair of drive springs symmetrically mounted in respect to the longitudinal axis of the projectile one adjacent each of said centrifugal weights, each of said symmetrically mounted springs having one end in engagement with the frame of the mechanism and having its other end in driving engagement with the corresponding pivotally mounted centrifugal weight, said centrifugal drive weights comprising disc members each having a mass mounted thereon so placed as to determine the maximum value of the centrifugal drive force and to determine the point in the time sequence at which the maximum will be exerted, said centrifugal weight discs being pivoted substantially centrally thereof, said symmetrical drive springs comprising coil springs mounted at the central pivots of said centrifugal weight discs, said masses on said discs each having a flattened face facing toward said pivot of the disc, said weight engaging ends of the symmetrical drive springs engaging said masses at said flattened faces thereof.

3. A fuse for projectiles having a time train and an escapement and a firing pin releasable by the time train, a pair of centrifugal drive weights pivotally mounted symmetrically in respect to the longitudinal axis of the projectile, a pair of drive springs symmetrically mounted in respect to the longitudinal axis of the projectile one adjacent each of said centrifugal weights, each of said symmetrically mounted springs having one end in

engagement with the frame of the mechanism and having its other end in driving engagement with the corresponding pivotally mounted centrifugal weight, said centrifugal drive weights comprising disc members each having a mass mounted thereon so placed as to determine the maximum value of the centrifugal drive force and to determine the point in the time sequence at which the maximum will be exerted, said centrifugal weight discs being pivoted substantially centrally thereof, said symmetrical drive springs comprising coil springs mounted at the central pivots of said centrifugal weight discs, said discs each having gear teeth cut in a portion of the periphery thereof for engaging a drive pinion and said discs each having an opening therein at the opposite side of the pivots to balance the discs, said frame engaging ends of said symmetrical drive springs engaging portions of said

frame which extend partially between said discs at opposite sides of said drive pinion.
